UNITED STATES PATENT OFFICE.

JAMES M. WALTERS, OF LOS ANGELES, CALIFORNIA.

DESIGN FOR A WINDOW-TRIMMER'S HAMMER.

47,906.

Specification for Design.

Patented Sept. 28, 1915.

Application filed May 15, 1915. Serial No. 28,469. Term of patent 14 years.

To all whom it may concern:

Be it known that I, JAMES M. WALTERS, a citizen of the United States, residing at Los Angeles, in the county of Los Angeles and State of California, have invented a new, original, and ornamental Design for a Window-Trimmer's Hammer, of which the following is a specification, reference being had to the accompanying drawing, forming part thereof.

The figure in said drawing is a perspective view showing my new design for hammer for window-trimmers.

I claim:

The ornamental design for window-trimmer's hammer, as shown.

JAMES M. WALTERS.

Witnesses:

J. B. SEXTON,

THOS. C. DE LISLE.
